UNITED STATES PATENT OFFICE.

CHRIS M. THOMSEN, OF POMONA, CALIFORNIA.

OIL STOVE.

Application filed July 28, 1927. Serial No. 209,086.

This invention relates to oil stoves and seeks to provide means for facilitating the lighting of the wick commonly employed in such devices, by very materially cutting down 5 the time and annoyance usually involved in the lighting of these devices.

The objectionable features above mentioned usually found are thought to be eliminated in the present invention by the provision of a pilot light associated with the principal wick of the burner, the pilot light remaining burning all the time. This pilot light being once started there is provided a 10 very easy means of igniting the main wick upon the mere turning on of the oil supply.

Referring to the drawings,

Figure 1 shows a top plan view of a conventional burner in which the invention has been placed.

20 Figure 2 is a vertical elevation of the burner showing the connection of the pilot with the oil supply.

Figure 3 is a fragmentary sectional view through the burner showing the construction 25 of the pilot, the figure being taken along line 3-3 of Figure 2.

Figure 4 is a fragmentary sectional view of the burner taken on the line 4-4 of Figure 3.

30 Referring more particularly to the drawings the burner consists of a casing 1 which is provided with a conventional wick 2, the wick being retained in place by the inner member 4, which is provided with air holes 5. Through this wick 2 is placed the pilot 3, the construction of which is shown in Figure 3. The pilot 3 is retained in position by the walls 9 which are tightly encased by the shell of 35 the principal burner and by the inner position of the members 9 which members are essential to a continuation of the walls of the pipe 8, hereinafter mentioned.

The member 10, representing the oil supply pipe is branched as shown at 8, the pipe 45 8 being bent in the shape of an elbow, the vertical portion of which carries the wick 3 to the pilot as above described. The burner 1 is provided with a clamp 11 which holds the burner in proper position.

50 In operation the supply of oil is turned on in the usual fashion and flows upward through the supply pipe 10, a portion of the supply of oil branching off through the member 8 and supplying the pilot 3. In this connection a column of oil will be trapped in the tube 10 when the oil supply valve (not

shown) is closed. This column of oil will be sufficient to keep the pilot wick burning for a considerable period of time. The pilot is lighted and remains lighted during the entire 60 time that the burner is desired to be used, it being capable of remaining lighted so long as there is a supply of fuel.

The fuel coming up through the pipe 10 fills the lower part of the burner 1 and saturates wick 2. It will be observed that when the oil supply valve above mentioned is closed the burner will become extinguished when the oil has burned from the upper or projecting edge of the wick 2. At this time the oil 70 trapped in the conduit 10 will be conducted to the pilot wick 3 to keep the same lighted. Due to the fact that the upper or projecting edge of the wick 2 is now dry, this wick will not become ignited. However, upon opening 75 the oil supply valve the oil will be conducted to the upper edge of the wick 2 and ignited by the pilot wick.

The provision of the pilot light assures a steady and continuous flame and permits the 80 lighting of the wick of the burner by means of this flame without the usual delay in turning the main wick into the igniting and burning positions, and also the delays incident to the saturating of this wick with the supply 85 of oil, thus avoiding a considerable amount of trouble and annoyance which usually accompanies the starting of this type of burner.

I claim:

1. In a pilot light, a liquid fuel burner, a 90 supply conduit communicating therewith and arranged to have communication with a source of liquid fuel and constituting a liquid fuel reservoir in which liquid fuel is trapped after the burner is extinguished, and a pilot 95 wick chamber in the burner and having communication with the supply conduit whereby the pilot wick chamber will be supplied with the trapped liquid fuel while the burner is not in operation.

2. In a liquid fuel burner pilot, a liquid fuel burner having a wick chamber, a vertical supply conduit leading therefrom to have communication with a liquid fuel reservoir and constituting a liquid fuel reservoir in 105 which liquid fuel is trapped after the burner is extinguished, a tubular member arranged vertically in the wick chamber and having communication with the supply conduit, and a pilot wick arranged in the tubular member 110 and receiving its supply from the vertical conduit while the burner is not in operation.

3. In a liquid fuel burner pilot, a liquid fuel burner having a wick chamber, a vertical supply conduit leading therefrom to have communication with a liquid fuel reservoir and constituting a liquid fuel auxiliary reservoir in which liquid fuel is trapped after the burner is extinguished, a branch pipe leading

from the supply conduit adjacent its upper end and extending through the wick chamber, and a normally lighted wick in the branch 10 pipe and adapted to ignite a wick arranged in the wick chamber when the upper edge of the latter is saturated with oil.

CHRIS M. THOMSEN.
